MULTIPLE IRONING MACHINE

John H. Leef, Minneapolis, Minn.

Application May 1, 1948, Serial No. 24,571

4 Claims. (Cl. 38—5)

1

My invention relates to garment ironers and, more specifically, to improvements in mounting a plurality of ironers in a circle or cluster so they may be tended by one or more operators with but a minimum of waste time and effort.

Garment ironers generally include a relatively fixed pressing shoe and a relatively movable pressing shoe which are conventionally manually separated for the insertion of garments therebetween and the removal of garments therefrom and are manually brought into pressing engagement and locked therein.

The primary object of my invention is the provision of a device wherein a plurality of such normally manually-operated ironers are mounted on an endless track for movements to and from an operator's station, and means for automatically operating the mechanism to move said shoes apart and out of and into pressing engagement at timed intervals adjacent the operator's station.

Another object of my invention is the provision of means whereby the automatic mechanism for bringing the pressing shoes into pressing engagement may be rendered inoperative during movements of the ironers on said track.

A still further object of my invention is the provision of means for successively operating the mechanisms of the several ironers to bring the shoes of said several ironers into and locking the same in pressing engagement when said ironers are moving in a direction away from the operator's station, and means adjacent the operator's station for successively unlocking and releasing said shoes from pressing engagement when said ironers are approaching the operator's station.

A still further object of my invention is the provision of a device of the class described and operating mechanism therefor which is relatively inexpensive to produce, rugged in construction, and durable in use.

Other novel features of the machine disclosed herein are disclosed and claimed in co-pending applications as follows: A. My co-pending application, Serial Number 144,341, filed February 15, 1950, as a continuation-in-part of this application; and B. My co-pending application, Serial Number 144,343, filed February 15, 1950, as a division of this application; both applications being entitled "Multiple Ironing Machine."

The still further objects of my invention will become apparent from the following detailed specification, appended claims, and attached drawings.

Referring to the drawings, wherein like char-

2

acters indicate like parts throughout the several views:

Fig. 1 is a plan illustrating a group of ironers mounted on a turntable in accordance with my invention and showing a preferred embodiment of my invention;

Fig. 2 is an enlarged fragmentary view, partly in side elevation and partly in section, taken on the line 2—2 of Fig. 1;

Fig. 3 is an enlarged fragmentary elevation as seen from the line 3—3 of Fig. 1;

Fig. 4 is a view corresponding to Fig. 3, but showing a different position of some of the parts;

Fig. 5 is an elevation, partly in section, taken on the line 5—5 of Fig. 3;

Fig. 6 is a view corresponding to Fig. 5 but taken substantially on the line 6—6 of Fig. 4;

Fig. 7 is an enlarged fragmentary view, taken substantially on the line 7—7 but showing a modified form of the invention;

Fig. 8 is an enlarged fragmentary detail taken on the line 8—8 of Fig. 7;

Fig. 9 is a fragmentary view, partly in section and partly in side elevation, taken on the line 9—9 of Fig. 7;

Fig. 10 is a view corresponding to Figs. 5 and 6, but illustrating a modified form of release mechanism used in conjunction with the mechanism of Figs. 7, 8, and 9;

Fig. 11 is a fragmentary view, partly in section and partly in side elevation, taken on the line 11—11 of Fig. 10;

Fig. 12 is a view corresponding to Fig. 2, but showing a still further modification of the invention;

Fig. 13 is a fragmentary detail, taken on the line 13—13 of Fig. 12;

Fig. 14 is a fragmentary detail in section, taken on the line 14—14 of Fig. 12;

Fig. 15 is a view in plan, taken substantially on the line 15—15 of Fig. 12; and

Fig. 16 is a diagram of a fluid pressure system for operating the machine of Fig. 12.

Referring with greater particularity to the structure of Figs. 1—6 inclusive, the numeral 1 indicates, in its entirety, a turntable comprising an annular supporting plate 2 secured to a concentric annular hub 3 by means of a plurality of radial arms 4. The plate 2 is reinforced by concentric annular flanges 5 and 6, the latter being in the nature of a structural angle iron. Depending spaced flanges 7 form bearing brackets journaling wheels 8 for rotation upon an endless circular track 9.

Mounted fast on the annular supporting plate

2 is a plurality of circumferentially-spaced pressing or ironing devices 10, each having a relatively stationary pressing shoe 11 and a relatively movable pressing shoe 12. As shown in Fig. 2, the fixed elements 11 are mounted on circumferentially-spaced pedestal-like bases 13. Each shoe 12 is provided with arms 14 rigidly secured thereto, projecting radially inwardly of the turntable and pivoted at their intermediate portions to their respective bases 13, as indicated at 15. At their radially inner ends, the arms 14 are provided with the customary counterweights 16. Each of the ironers 10 have identical linkage for moving their respective movable shoes 12 from the full line position of Fig. 2 to the dotted line position thereof and vice versa. For the sake of brevity, but one of the operating linkage units will be described.

A toggle link 17 has its upper end pivoted to the arm 14 intermediate the pivot 15 and the counterweighted end 16, as indicated at 18. The lower end of the toggle link 17 is pivotally connected to a second toggle link 19, as indicated at 20, which toggle link 19 has its lower end pivoted to the base 13, as indicated at 21. A treadle 22 is pivotally secured to the base 13, as indicated at 23, and projects radially outwardly of the base 13 and turntable 1 through a slot 24 in the base 13. A generally vertically-disposed link 25 has its lower end pivoted to the intermediate portion 26 of the treadle 22 and has its upper end pivoted to one end of a lever arm 27, as indicated at 28. The lever arm 27 is mounted for rocking movements on a rock shaft 29 extending transversely of the base 13 and has its inwardly-projected end coupled to the intermediate portion 30 of the toggle link 19 by means of a relatively short link 31 which is connected to the radially-inner end of the lever arm 27 as at 32. It will be obvious, by reference to Fig. 2, that downward movement of the treadle 22 will cause movement of the movable shoe 12 in the direction of the relatively fixed shoe 11, as indicated by full line. Conversely, upward movement of the treadle 22 will cause movements of the movable shoe 12 in a direction away from the stationary shoe 11, as indicated by dotted line in Fig. 2. A coil tension spring 33 has one end secured to the vertical link 25 and its opposite end anchored to the base 13, whereby to bias the treadle in an upward direction to move the shoe 12 in a direction away from the relatively fixed shoe 11. A stop screw 34 limits movement of the linkage and consequent movement of the movable shoe 12 in the direction of the fixed shoe 11.

The several ironers are provided with means for locking the treadles 22 thereof in their depressed positions as best shown in Figs. 3-7 inclusive. On each of the several ironers 10, said means includes a laterally-projecting pin 35 adjacent the outer end of the treadle 22 adapted to have sliding engagement with an arm 36 pivoted at its lower end to a bracket 37 secured to the radially outer surface of the base 13. The arm 36 is yieldingly biased in the direction of the pin 35 by means of a coil compression spring 38 and is provided with an offset portion intermediate its ends which forms a recess 39 in which the pin 35 is seated when the treadle 22 is in its extreme depressed position as shown in Fig. 5. A release pedal 40 is pivotally secured to the base 13, as indicated at 41, and extends radially outwardly of the turntable 1 at one side of the treadle 22 and parallel thereto. A bell crank 42 has its

intermediate portion pivotally secured to the release lever 40, as indicated at 43, and has one of its arms 44 held against vertical swinging movements by means of a rigid link 45 secured thereto and to the base 13, as indicated at 46 (see particularly Figs. 2, 5, and 6). The other arm 47 of the bell crank 42 extends generally upwardly and is adapted to engage a laterally-projecting lug 48 on the arm 36. Downward movement 10 of the release pedal or lever 40 causes the arm 47 to swing radially inwardly with respect to the turntable and consequent movement in a direction radially inwardly of the turntable of the arm 36, against bias of the spring 38, as best shown in Figs. 5 and 6. This inward movement of the arm 36 releases the laterally-projecting pin 35 from the recess 39 and allows bias of the tension spring 33 to move the treadle 22 in an upward direction and consequent movement of the relatively movable shoe 12 in a direction away from the relatively fixed shoe 11. A coil tension spring 49 has one end anchored to the release pedal 40 and its other end to the base 13, whereby to bias the release pedal 40 in an upward direction.

I provide an inlet pipe 50, the lower end of which is rotatively connected to the upper portion of a steam manifold 51 through a packing gland 52. The upper or input portion 53 of the manifold 51 is divided from the lower or exhaust portion 54 thereof by a partition 55 having therein a central drain orifice 56. A plurality of flexible inlet tubes 57 lead one each from the input chamber 53 of the manifold 51 to one of the movable shoes 12. The shoes 12 are each provided with flexible drain pipes or tubes 58 that are connected to the lower exhaust portion 54 of the manifold 51. The inlet tubes 57 and the drain tubes 58, being flexible in nature, do not interfere with the freedom of movement of the relatively movable shoes 12. Condensate from the shoes 12 passes through the tubes 58 into the exhaust chamber 54 from whence it is removed from a drain pipe 59 through a packing gland 60. It will be seen, particularly by reference to Figs. 1 and 2, that the manifold 51 overlies and is concentric with the hub 3 of the turntable 1 and that the flexible tubes 57 and 58 radiate outwardly from the manifold 51 to their respective shoes 12.

Continuous and uninterrupted rotary movement is imparted to the turntable 1 by a motor 61 (see Fig. 1) which drives a shaft 62 through connections not shown but contained within a gear box 63. A sprocket wheel 64 is secured fast to the shaft 62 and positively drives a link chain 65 which extends about and is carried within a channel 66 formed by the outer peripheral portion of the annular plate 2 and the flange 6. The chain 65 is maintained in frictional driving contact with the flange 6 by means of an idler pulley 67 journalled to one arm of a bell crank 68 that is pivoted to a stationary quadrant 69. Pin and socket connections 70 of conventional design are utilized to maintain the idler 67 in a position to tighten the link chain 65. Obviously, moving the bell crank 68 in a counter-clockwise direction with respect to Fig. 1, will loosen the link chain 65 in the channel 66. This arrangement provides an inexpensive but very satisfactory drive for the turntable 1. It will be observed that the turntable 1 rotates in a clockwise direction with respect to and as shown by arrows in Fig. 1.

I provide means adjacent the periphery of the turntable 1 and to one side of an operator's station x for automatically and successively depress-

ing the several treadles 22 upon rotation of the turntable 1. The pedal-depressing means is in the nature of an elongated arcuate cam element 71 which lies in the path of travel of the radially outer ends of the several treadles 22 and is adapted to engage a roller 72 pivotally secured to a bracket 73 fast on the outer end of each treadle 22 (see particularly Figs. 1 and 2). The cam element 71 is supported on a base member 74 which is pivotally mounted at one end at 75 to the floor or other supporting structure. The opposite end of the base member 74 is slidably confined within an arcuate guideway 76. The cam 71 and base member 74 may be swung about the axis 75 from the full line treadle-intercepting position shown in Fig. 1 to the dotted line position thereof wherein the cam is disposed out of the path of travel of the several treadles 22, thereby rendering cam 71 inoperative. A suitable lock means such as a pin 77 may be inserted through openings 78 at either end of the arcuate guideway 76, whereby to maintain the cam 71 in either of its extreme positions.

As each treadle 22 is depressed by the cam 71, the projecting pins 35 of the treadles 22 move downwardly with respect to the arms 36 and become seated in the recess 39 thereof under bias of the spring 38 against the upper end of the arm 36, as clearly shown in Fig. 5.

I provide means for automatically and successively releasing said treadles 22 from their depressed positions, whereby to move the relatively movable shoes 12 away from the relatively stationary shoes 11, said means being located adjacent the outer periphery of the turntable 1 and adjacent the opposite side of the operator's station x from the cam 71. An arm 79 is mounted fast on one end of a rock shaft 80 journaled in a supporting frame 81. The arm 79 is formed with a cam surface 82, which normally lies in the path of travel of a plurality of cam followers in the nature of rollers 83 journaled in bearing brackets 84 fast on the underside of the turntable 1. The arm 79 is yieldingly biased toward the path of travel of the rollers 83 by a coil compression spring or the like 85. A rigid arm 86 extends generally upwardly from the outer end of the shaft 80 to which it is rigidly secured, and at its upper end has pin and slot connection, as indicated at 87 with a relatively short arm 88 fast on the outer end of a rock shaft 89 journaled in the upper end of the supporting frame 81. The rock shafts 89 and 80 extend generally radially of the turntable 1 and the radially inner end of rock shaft 89 is provided with a trip finger 90 secured fast thereto. The trip finger 90 overlies the path of travel of the trip lever or pedal 40 upon rotation of the turntable 1. The rollers 83 are in number equal to the several ironers 10 and so spaced with respect thereto that each roller will engage the cam surface 82 of the arm 79 just prior to the arrival of its cooperating ironer 10 at the operator's station x. Movement of the roller 83 from the right to the left with respect to Figs. 3 and 4 will cause downward movement of the arms 79 against bias of the spring 85, and consequent movement of the arms 86 and 88 from the position shown in Figs. 3 and 5 to that shown in Figs. 4 and 6. This movement of the arms 79, 86 and 88 causes downward movement of the trip finger 90 to an extent that the release pedal 40 is engaged by the trip finger 90 and moved from the position of Fig. 5 to that of Fig. 6. As hereinbefore described, downward movement of the release pedal 40 will cause the arm 47

of the bell crank 42 to engage the lug 48 of the pivoted arm 36 and move the arm 36 against bias of the spring 38 to release the treadle 22. Obviously, continued rotary movement of the turntable 1 will bring successive release pedals 40 into position to be engaged by the trip finger 90. As will be seen from Figs. 3 to 6, inclusive, the trip finger 90 overlies the path of travel of the release pedals 40, and is so situated with respect to the radially outer end of the treadle 22 so that it overlies the path of travel thereof when the treadle 22 is depressed, and underlies the path of travel thereof when said treadle is in its elevated position of Fig. 6.

15 In operation, the cam 71 and base thereof 74 is moved to the full line position of Fig. 1, and rotary motion is imparted to the turntable 1. As each ironer 10 passes the operator's station x, a garment to be ironed is placed upon the relatively 20 stationary shoe 11 thereof. When said ironer has passed the operator's station x, the cam roller 72 passes under and is engaged by the cam 71. Continued movement of the turntable 1 causes the cam 71 to depress the treadle 22 until the 25 movable shoe 12 has moved from its dotted line position of Fig. 2 to the full line position thereof to press the garment therebetween. At this point, the pin 35 becomes seated in the recess 39 of the pivoted arm 36, thereby temporarily locking 30 the movable element 12 in pressing or ironing engagement with the relatively fixed shoe 11. This operation is repeated on each successive ironer as it leaves the operator's station x upon clockwise rotation of the turntable 1 with respect 35 to Fig. 1. When each ironer 10 has progressed to a point prior to its reaching the operator's station again, its cooperating roller 83 will engage the cam surface 82 of the pivoted arm 79 whereby to cause the trip finger 90 to engage and depress 40 the release lever 40. As hereinbefore described, depression of the release pedal 40 will allow the treadle 22 to move upwardly, thereby causing the relatively movable shoe 12 to move away from engagement with the relatively fixed shoe 11 under bias of the spring 38. When it is desired 45 to shut the machine down for any length of time, it is necessary to maintain the several shoes 12 out of engagement with their cooperating shoes 11. This is accomplished by merely removing the pin 77 from one of the apertures 78 in the guideway 76 and moving the cam 71 to the dotted line position of Fig. 1, where it will be out of the path of travel of the several treadles 22. Rotation of turntable 1 will cause the trip finger 90 to successively engage each release pedal 40 whereby 50 to move the shoes 12 away from their cooperating shoes 11 until all of the ironers have been placed in an open condition. By this arrangement, heating medium, such as live steam, may 55 continue to be admitted to the several shoes 12 without danger of scorching padding and fabric covering customarily used on the stationary shoes 11.

60 Referring now to the structure of Figs. 7-11 inclusive, wherein modified means for depressing the treadle 22 and releasing the same is illustrated, parts identical to those of Figs. 1-6, inclusive are identified by the same characters. In this connection, however, it will be noted that the rigid link 45 of Figs. 1-6 inclusive has been removed and a rigid link 45' substituted therefor. The link 45' is rigidly secured to a bracket 91, which is in turn rigidly secured to the base 13 by means of screws or the like 92. For depressing the treadle 22, I provide fluid pressure-operated

means in the nature of cylinder 93 and piston 94 mounted for reciprocal movements therein. The cylinder 93 is vertically axially held in a position overlying the path of travel of the treadle 22 by means of a supporting frame 95 rigidly secured to the floor or other supporting means by screws or the like 96. A piston rod 97 extends downwardly through one end of the cylinder 93 and is provided at its end with a laterally-projecting foot 98 which is adapted to engage a roller 72' mounted on the outer end of the treadle 22 by means of a bearing bracket 73'. The piston 94 and piston rod 97 are yieldingly biased in a direction away from engagement with the rollers 72' by means of a coil compression spring 99. Fluid under pressure is admitted to one end of the cylinder 93 from a source of fluid pressure not shown, by conduit means 100. A three-way valve 101 is interposed in the conduit means 100 and is secured to the supporting frame 95 by means of machine screws or the like 102. The valve 101 may be of any particular type but preferably and as shown is provided with a rotary plug 103 which is chambered to allow fluid under pressure to pass therethrough from the source of pressure to the cylinder 93. The plug 103 may be turned to allow passage of fluid from the cylinder 93 to atmosphere through a port 104 in the valve 101. The plug 103 extends outwardly through the body of the valve 101 and has rigidly secured to the outer end thereof a pair of circumferentially-spaced operating fingers 105 and 106 that are adapted to engage, upon rotation of the turntable 1, valve-operating lugs 107 and 108 respectively. Lugs 107 and 108 are mounted one each on the base 13 in vertical and horizontally-spaced relationship. I also provide a manually-controlled shut-off valve 109 in the conduit means between the source of pressure and the three-way valve 101 and located at a point within easy reach of the operator of the machine.

Movement of the turntable in a direction from the right to the left with respect to Fig. 9 causes the lug 108 to engage the operating finger 106 and move the same to a point where the chamber of the plug 103 will admit fluid under pressure from the source of pressure to the cylinder 93. Pressure within the cylinder 93 will be sufficient to move the piston 94 against bias of the spring 99 and cause the foot 98 to engage the rollers 72' passing thereunder and depress the treadle 22 to its extreme downward position where it will be locked by the mechanism heretofore described. Continued movement of the turntable from the right to the left with respect to Fig. 9 causes the lug 107 to engage the valve-operating finger 105 and move the same and the plug 103 to a position whereby fluid is allowed to flow from the cylinder 93 to atmosphere through the port 104 under bias of the spring 99 against the piston 94. The operating fingers 105 and 106 are so arranged that when the lug 108 has moved the operating finger 106 to its desired position, the outer end of the finger 106 will be moved upwardly to a point where the lug 108 may pass thereunder. This movement of the finger 106 causes the finger 105 to be moved to a point where it may be engaged by the lug 107 upon continued movement of the turntable. Similarly, when the lug 107 has moved the finger 105 to a point where fluid is allowed to escape from the cylinder 93 to atmosphere through the valve 101, the outer end of the finger 105 will become depressed to a point where the lug 107 may pass thereover. It will be noted

that the structure of Fig. 7 is a modification of the cam means 71 of Figs. 1 and 2 and is located on the same side of the operator's station as the cam means 71.

Fluid pressure-operated means for releasing the treadles 22 from their locked depressed position is in the nature of fluid pressure-operated means comprising a cylinder 110, a piston 111 mounted for reciprocation therein, and a piston rod 112 connected to said piston 111 and projecting axially outwardly of the cylinder 110, and operating connections therebetween and the release pedal 40. The cylinder 110 is pivotally connected as indicated at 113 to a supporting frame 114 which is located adjacent the turntable 1 and at the opposite side of the operator's station x from the frame 95 and structure carried thereby. A rocker arm 115 is intermediately pivoted, as indicated, at 116, to the upper end of the supporting frame 114 and has its outer end pivotally connected to the upper end of the piston rod 112 as at 117. At its inner end, the rocker arm 115 is formed to provide bearings which journal a roller 118 that overlies the path of travel of the release pedal 40. Fluid under pressure from a source not shown is admitted to the cylinder 110 through a conduit 119 and a three-way valve 120, said valve being secured fast to the supporting frame 114 by means of screws or the like 121. The valve 120 is similar to the valve 101 having therein a rotary lug 122 which is chambered to allow fluid under pressure to be admitted to the interior of the cylinder 110 through the conduit 119. The plug 122 is rotatable, whereby to allow fluid to escape from the cylinder 110 through the conduit 119 to atmosphere through a port 123 in the valve 120. The plug 122 extends outwardly of the valve 120 and terminates in a pair of circumferentially-spaced radially-projecting fingers 124 and 125 which are adapted to be engaged and moved by respective radially-projecting lugs 126 and 127 on the turntable 1.

As a given ironer 10 approaches the operator's station x, the lug 127 for its respective ironer 10 will engage and move the operating finger 125 and thereby cause rotation of the plug 122 to permit fluid under pressure to enter the cylinder 110. Resulting movement of the piston 111 and piston rod 112 in an upward direction will cause rocking movement of the rocker arm 115 and engagement of the release pedal 40 by the roller 118. Continued downward movement of the roller 118 will cause the release lever 40 to disengage the locking means from the treadle 22 and allow the same to move upwardly to the dotted line position of Fig. 10, wherein it may be assumed that the movable shoe 12 connected therewith will be moved away from its cooperating relatively fixed shoe 12. As the lug 126 moves from the right to the left with respect to Fig. 11 upon rotary movement of the turntable 1, the plug 122 will be rotated to a point where fluid will be allowed to escape from the cylinder 110 to atmosphere through the port 123. As the lug 126 progresses from the right to the left, it will pass over the outer end of the finger 124, and the operating finger 125 will be moved to its dotted line position of Fig. 11, where it will be engageable with the next successive lug 127.

When it is desired to suspend operations of the machine of Fig. 1 equipped with the apparatus of Figs. 7-11 inclusive, the shut-off valve 109 is manipulated to prevent fluid under pressure from entering the cylinder 93. Thus, the

piston 94 and piston rod 97 will be rendered inoperative to depress the treadles 22, and, under continued rotation of the turntable 1, all ironers will be placed in an open condition and remain so until the shut-off valve 109 is again opened. In other words, the shut-off valve 109 serves the same purpose as movement of the cam 71 out of the path of travel of the treadles 22 in Figs. 1 and 2.

Coming now to the modified structure illustrated in Figs. 12-15 inclusive, the turntable is identified by the numeral 1' having an annular supporting plate 2' supported by wheels 8' running on an endless circular track 9'. A plurality of ironers 10', one of which is shown, is carried by the turntable 1' and each comprises a relatively stationary shoe 11' and a relatively movable shoe 12'. Relatively fixed shoe 11' is carried on a base 13'. The relatively movable shoe 12' is rigidly secured to one end of a radially inwardly-projecting arm 14' which is pivoted intermediate its ends to the base 13', as indicated at 15'. Pivots secured to the radially inwardly-extended end of the arm 14', as indicated at 128, is an adjustable link 129. The lower end of the link 129 is provided with a roller not shown which is adapted to ride in cam slot 130 in a vertical bracket 131 secured to the turntable 1'. Also pivotally secured to the lower end of the link 129 is the outer end of a piston rod 132 which is equipped with a piston not shown but contained within a fluid pressure-operated cylinder 133 hingedly secured, as indicated at 134, to the frame base 13'. A second fluid pressure-operated cylinder 135 is pivotally secured to the frame 13', as indicated at 136, and is provided with a piston-equipped rod 137 which has pivotal engagement with the arm 14' intermediate its pivot 15' and its inner end, as indicated at 138. The movable shoe 12' is biased away from engagement from the relatively fixed shoe 11' by means of a tension spring 139 anchored at one end to the turntable 1' and at its other end to the intermediate portion of the link 129.

The movable shoe 12' may be heated by any suitable means such as live steam introduced thereto from a suitable source of supply not shown through an inlet pipe 140. The inlet pipe 140 has a packing gland connection 141 to the inlet chamber 142 of a steam manifold 143. Pipes 144 extend radially outwardly from the manifold chamber 142 and have connection with flexible inlet tubes 145 leading to the several movable shoes 12'. Flexible exhaust tubes 146 lead from the movable shoes 12' to radially-projecting pipes 147 that are connected to exhaust chamber 148 of the manifold 143. A suitable drain pipe 149 is connected to the exhaust chamber 148 by means of a packing gland 150. The packing gland connections 141 and 150 allow rotation of the steam manifold 143 while the inlet pipe 140 and drain pipe 149 remain in a stationary condition.

Fluid under pressure is supplied to the several ironers for moving the relatively movable shoes 12' from a source of fluid supply not shown through a pipe 151 which extends upwardly through the packing gland 150 and the manifold exhaust chamber 148 by means of suitable rotary joints or slip connections 152. The pipe 151 extends radially outwardly of the steam manifold 143 and branches off to the several ironers on the turntable 1', as indicated at 153. One of the branches 154 extends from the connection 75

152 to a reversing valve 155. From thence, conduit means 156 and 157 lead to respective cylinders 133 and 135. The valve 155 has a port open to atmosphere through a short conduit 158 and a muffler 159. The reversing valve 155 is operated by a fluid pressure-operated reversing motor comprising axially-aligned fluid pressure cylinders 160 and 161 provided with pistons not shown and having a common piston rod 162. A collar 163 fast on the piston rod 162 has pin-and-slot connection 164 with an arm 165 which is connected to and projects radially outwardly from a plug 166 rotatively mounted in the valve 155. The plug 166 is chambered to allow fluid under pressure to enter the cylinders 133 and 135 in one position thereof and in another position thereof to allow air to escape from the cylinder 133 and 135 to atmosphere through the conduit 158 and muffler 159. Fluid under pressure is supplied to the cylinders 160 and 161 from the conduit means 154 by means of branch conduit 167 which leads to a pair of pilot valves 168 and 169. Pipes 170 and 171 lead from the pilot valve 168 to the cylinder 160 and from the pilot valve 169 to the cylinder 161 respectively. The pilot valves 168 and 169 are of the well-known type having opposed valve seats and valve elements therefor, the valve elements each carried by a reciprocal stem 172 yieldingly biased in one direction by a spring 173 (see particularly Fig. 16). The pilot valves are further provided with exhaust passages 174 leading to atmosphere. Movement of the stem 172 of the pilot valve 168 against bias of the spring 173 allows fluid under pressure to flow through the conduit 167, conduit 170, and into the cylinder 160, whereby to move the collar 163 on the piston rod 162 from the left to the right with respect to Fig. 16. This will rotate the plug 166 of the valve 155 to a position to allow fluid to escape from the cylinders 133 and 135 to atmosphere through the muffler 159. Simultaneous movement of the pistons carried by the cylinders 160 and 161 from the left to the right with respect to Fig. 16, causes fluid contained within the cylinder 161 to be passed through the conduit 171 to atmosphere through the exhaust passage 174 in the pilot valve 169. Similarly, movement of the stem 172 of the valve 169 against bias of the spring 173 will allow fluid under pressure to flow through the conduit 167, valve 169, and passages 171 into the cylinder 161, whereby to move the piston-equipped rod 162 and collar 163 from the right to the left with respect to Fig. 16, thereby causing rotation of the plug 166 to allow passage of fluid under pressure to the cylinders 133 and 135. Consequent outward movement of the piston rods 132 and 137 will move the arm 14' and shoe 12' toward locking engagement with the relatively fixed shoe 11'. It will be seen, by reference to Fig. 12, that initial movement of the shoe 12' is caused by outward movement of the piston rod 137 and that final pressing action is affected by outward movement of the piston rod 132 during the final movement of the shoe 12' toward the shoe 11'. This final locking pressure between the shoes 11' and 12' is made effective by the engagement of the roller not shown, but at the pivotal connection between the link 129 and piston rod 132, with the extreme upper end of the cam slot 130. Generally, in machines of this type, the reciprocal valve stems 172 are moved by button-equipped push rods 175, one of which is shown, pivotally connected to the outer ends of bell cranks 176 that are pivoted to the base 13', as indicated at 177.

For operating the pilot valve 169, I provide an elongated segmental cam track 178 located adjacent the track 9' beneath the turntable 1' and which may be assumed to be positioned similar to the cam 71 with respect to the operator's station x. A cam follower, indicated in its entirety by the numeral 179, is illustrated in Figs. 12 and 14 and comprises a lever arm 180 pivotally secured intermediate its ends to the turntable 1' as indicated at 181, and a roller 182 journalled at one end thereof. A rigid link 183, pivotally secured to the opposite end of the lever 180, extends upwardly through an opening in the annular plate 2', and terminates in a pivotal connection 184 with one arm of a bell crank 185, which is pivotally mounted to the base 13' by means of a bracket 186. A push rod 187 has its lower end pivoted to the other arm of the bell crank 185, as indicated at 188, and has its upper end pivotally secured to the pivotal connection 189 between the bell crank 176 and the push rod 175.

During the greater part of rotation of the turntable 1', the roller 182 is suspended above the floor or ground, as indicated in Fig. 13. A bell crank 190 has its intermediate portion pivoted to the lever 180 intermediate the roller 182 and the pivot 181, as indicated at 191. One arm of the bell crank 190 extends in a generally horizontal direction and has journalled to the outer end thereof a roller 192 which normally lies in the same horizontal plane as the roller 182. As shown in Fig. 13, the other arm of the bell crank 190 extends generally upwardly and, at its end, is notched to engage a stop lug 193 secured to the turntable 1'. The cam track 178 lies in the path of travel of the rollers 192 and 182 and with the turntable rotating in the proper direction as indicated by arrows in Figs. 13 and 14, the cam track will first engage and raise the roller 192 and, while the same is still carried thereby in a raised position, will engage and raise the roller 182. Raising of the roller 192 causes movement of the notched arm of the bell crank 190 away from the stop lug 193, whereby to allow raising of the roller 182 by the cam track 178. As indicated in Figs. 13 and 14, the roller 182 cannot be elevated unless the roller 192 is in an elevated position, because of the engagement of the notched portion of the bell crank with the stop lug 193 when the roller 192 is in its lower position. Hence, if any foreign material, such as a block of wood or the like, happens to be inadvertently thrown under the turntable in the path of travel of the rollers 192 and 182, the roller 192 may be elevated thereby and thereafter dropped to its lower position before the roller 182 is engaged by said foreign material. Thus, when the roller 182 comes into contact with the foreign material, the lever 180 is held against upward movement and the foreign material will be pushed out of the way by the roller 182, or the resistance set up by the foreign material may be sufficient to stop rotation of the turntable 1'. In any event, with this arrangement, the mechanism cannot be operated to lower the shoe 12' into pressing engagement with the shoe 11', unless both of the rollers 182 and 192 are in their elevated positions as when on the cam track 178.

The cam track 178 is movable in a direction radially of the turntable 1' into and out of the path of travel of the cam follower 179 in a pair of spaced guides 194 which are suitably secured to the floor. The cam track has a

radially-extending leg 195 to the end of which is pivotally secured one end of a lever 196, which is centrally pivoted to the floor, as indicated at 197. The other opposite end of the lever 196 is pivotally secured to one end of a shifter handle 198 which extends radially outwardly beyond the turntable 1' where it may be grasped by the operator. Suitable means, such as a pin 199, may be inserted into either one of a pair of apertures 200 in the floor radially outwardly of the turntable 1'. By reference to Fig. 15, it will be noted that but one of the apertures 200 is shown, the other being assumed to underlie the pin 199. The full lines in Fig. 15 illustrate the cam track in position to engage the cam follower 179, whereas the dotted lines indicate the position assumed by the cam track when it is moved to its inoperative position radially inwardly of the path of travel of the cam follower 179.

A cam follower, identical in all respects to the cam follower 179, is indicated in its entirety by the numeral 201 and comprises a roller-equipped lever 202 and a roller-equipped bell crank 203. With reference to Fig. 12, it will be seen that the cam follower 201 is radially offset from the cam follower 179 and is adapted to engage a stationary cam track not shown but lying in the path thereof and on the opposite side of the operator's station from the cam track 178. A rigid link 204, similar to link 183, extends upwardly from one end of the lever 202 and has its upper end pivotally secured to one end of a bell crank 205, which is pivotally mounted on a bracket 206 mounted fast on the base 13'. The other arm of the bell crank 205 has pivotal connection with a push rod 207 which, at its upper end, is secured to the bell crank not shown but which is adapted to work against the valve stem 172 of the pilot valve 168. It will, of course, be understood that each ironer 10' is equipped with cam followers 179 and 201 and, as each particular ironer 10' leaves the operator's station with a garment placed upon the shoe 11', the cam follower 179 rides over the cam track 178. Upward movement of the roller-equipped end of lever 180 results in a downward movement of the rigid link 183 and associated push rod 187, whereby to open the pilot valve 169 and admit fluid under pressure through the conduits 167 and 171 to the cylinder 161. Air under pressure entering the cylinder 161 moves the piston-equipped rod 162 from the right to the left with respect to Fig. 16 to position the valve plug 166, as therein shown. Thus, fluid under pressure is admitted through the conduits 156 and 157 to the cylinders 133 and 135 respectively, whereby to move the relatively movable shoe 12' into pressing engagement with the relatively fixed shoe 11' against bias of the spring 139. Upon continued rotation of the turntable 1' as each ironer 10' approaches the operator's station, the cam follower 201 is engaged by the cam track not shown but assumed to be lying in the path thereof. Consequent upward movement of the roller-equipped lever 202 results in downward movement of the rigid link 204 and push rod 207 and consequent opening of the pilot valve 168. When the pilot valve 168 is opened against bias of the spring 173 thereof, fluid under pressure is admitted through conduits 167 and 170 to the cylinder 160 causing movement of the piston-equipped piston rod 162 from the left to the right with respect to Fig. 16, thus turning the plug 166 of the valve 155 to a position to allow fluid to escape from the cylinders 133 and 135 to

atmosphere through the muffler 159. Yielding bias of the spring 139 moves the link 129 and arm 14' in a direction to move the shoe 12' away from engagement with the shoe 11' and causes the piston rods 132 and 137 to move in the direction of their respective cylinders 133 and 135, thereby forcing the fluid therefrom to atmosphere. The ironer 10' is then in a position to have the ironed garment removed therefrom and an unironed garment applied thereto.

When it is desired to shut down the machine of Figs. 12 to 16 inclusive, the cam track 178 is manually moved out of the path of travel of the cam follower 179 by manipulation of the shifter handle 198 from the full line position of Fig. 15 to the dotted line position thereof. Upon continued rotation of the turntable 1, each ironer 10' will be opened as its respective cam follower 201 is engaged by the cam track lying in the path thereof, but no subsequent closing action is imparted to the movable shoe 12'. The turntable 1' is made to rotate until all of the ironers 10' have been opened. When this is done, rotation of the turntable may be stopped and there will be no danger of the padding or fabric covering of the stationary shoe 11' being scorched by the heated shoe 12' as would be the case if the shoes 11' and 12' were in pressing contact for any protracted length of time.

It is understood that the ironers herein disclosed are in themselves old in the art. I have found that by mounting these ironers on a turntable as shown and automatically controlling the movements of the movable shoes with respect to the relatively fixed shoes thereof, I have been able to effect a great savings in time and labor in the ironing of various garments on a production scale.

Although the foregoing description is necessarily of detailed character, in order that the invention may be completely set forth, it is to be understood that the specific terminology is not intended to be restrictive or confining and that various rearrangement of parts and modifications of detail may be resorted to without departing from the scope and spirit of the invention as herein claimed.

What I claim is:

1. In a device of the class described, an endless track, a garment ironer movably mounted on said track, said garment ironer comprising relatively fixed and movable shoes, linkage operatively associated with said ironer for moving said movable shoe toward and away from said relatively fixed shoe, each of said linkages including an operating treadle which projects radially outwardly from said ironer, cam means adjacent said track and in the path of travel of said treadle upon movement of said ironer about said track for imparting movements to said treadle and linkage to move said movable shoe toward said relatively fixed shoe, means locking said treadle in set position when said shoes are moved to pressing engagement, mechanism for unlocking said treadle and said shoes including a release lever, a second cam means comprising a relatively fixed cam element on said ironer for movement therewith about said track, a relatively movable cam element mounted for pivotal movements in a supporting frame in the path of travel of said relatively fixed element, a trip finger pivoted to said frame and movable toward and from operative engagement with said release lever, and motion transfer means between said movable cam element and said trip finger for moving said trip

70

75

76

finger when said movable cam element is engaged by said relatively fixed cam element.

2. In a device of the class described, an endless circular track, a plurality of circumferentially-spaced garment ironers movably mounted on said track, each of said ironers comprising a relatively fixed and relatively movable pressing shoe, linkage operatively associated with each of said ironers for moving said relatively movable shoes toward and from said relatively fixed shoes, an operator's station adjacent said track for application of garments to said ironers and removal of garments therefrom, means adjacent said track and one side of said operator's station and in the path of travel of said ironers upon movement of said ironers upon said track for successively imparting movements to said linkages to move said relatively movable shoes away from said relatively fixed shoes, means adjacent said track and the opposite side of said operator's station and in the path of travel of said ironers upon movement of said ironers upon said track for successively imparting movements to said linkages to move said relatively movable shoes toward said relatively fixed shoes, and means for rendering said last-mentioned means inoperative during the travel of said ironers about said track, each of said linkages terminating in a cam-operated element projecting radially outwardly from said track, said first-mentioned means including a cam element in the path of travel of said cam-operated elements, said cam element being laterally shiftable out of the path of travel of said cam-operated elements.

3. In a device of the class described, an endless track, a plurality of circumferentially-spaced garment ironers movably mounted on said track, means for simultaneously imparting to said ironers continuous and uninterrupted movement about said track, each of said ironers comprising relatively fixed and movable pressing shoes, linkage operatively associated with each of said ironers for moving said relatively movable shoes toward and from said relatively fixed shoes, an operator's station adjacent said track for application of garments to said ironers and removal of garments therefrom, means adjacent said track and in advance of the operator's station and in the path of travel of said ironers upon movement of said ironers upon said track for successively imparting movements to said linkages to move said relatively movable shoes away from said relatively fixed shoes, means adjacent said track and to the rear of said operator's station and in the path of travel of said ironers upon movement of said ironers upon said track for successively imparting movements to said linkages to move said relatively movable shoes toward said relatively fixed shoes, said last-mentioned means being manually movable out of the path of travel of said linkages whereby to render said linkages inoperative.

4. In a device of the class described, an endless track, a garment ironer movably mounted on said track, said garment ironer comprising relatively fixed and movable shoes, linkage operatively associated with said ironer for moving said movable shoe toward and away from said relatively fixed shoe and comprising a cam-operated member, cam means adjacent said track and in the path of travel of said cam-operated member upon movement of said ironer about said track for imparting movements to said member and linkage to move said movable shoe toward said relatively fixed shoe, means locking said cam-operated

15

member in said position when said shoes are moved to pressing engagement, mechanism for unlocking said member and said shoes including a release lever, a second cam means comprising a relatively fixed cam element on said ironer for movement therewith about said track, a relatively movable cam element mounted for pivotal movements in a supporting frame in the path of travel of said relatively fixed element, a trip finger pivoted to said frame and movable toward and from operative engagement with said release lever, and motion transfer means between said movable cam element and said trip finger for

5

moving said trip finger when said movable cam element is engaged by said relatively fixed cam element.
